UNITED STATES PATENT OFFICE.

DAVID C. FEATHER, OF FORT MORGAN, COLORADO, ASSIGNOR TO IRA J. CLARK, OF DENVER, COLORADO.

SPRING COMPRESSOR AND CARRIER-HOLDING TOOL.

Application filed April 24, 1924. Serial No. 708,710.

This invention relates to improvements in spring removers and applicers, and particularly embodies a spring compressor and carrier holding tool which is of unique structure in itself, and functions in a materially improved manner, as will hereinafter appear.

One of the objects of my invention has been to devise a simple, durable and effective tool, adapted for substantially all analogous conditions relating to the removal and replacement of coil springs generally, which tool is of a self-guiding and centering double movable jaw type, for leverage engagement with both end portions of the coil spring, in bridged or straddled gripping relation, so that said end portions are caused to be compressed towards the central portion, whereby the improved tool not only functions as a compressor means, for the spring, but also serves as a carrier holding means or support for the removal and replacement of said spring, while so compressed, features of no little importance in point of economy of time and the avoiding of annoyances, and which will readily be recognized by the individual users of such tools generally, as well as to the garage and other repair industries in particular.

The foregoing and other objects and advantages, however, will be more clearly apparent as incidental to the following disclosure, and with these prefacing remarks, therefore, reference will now be immediately had to the accompanying drawings, illustrating practical embodiments of the improvements, although not essentially the only ones, and the application of the improved tool in certain relations, in which drawings—

Figure 1 is a top plan view of one form of the improved tool;

Figure 2 is a view of the same, shown in closed up position in full lines, partly in side elevation and partly in vertical longitudinal section, along the line 2—2 of Figure 1, the opened out positions of the parts being also shown in dotted outline;

Figures 3 and 4 are local transverse cross-sectional views taken along the lines 3 and 4, respectively, of Figure 2;

Figure 4^a is a fragmentary top plan view of a slightly modified structure;

Figures 5 and 6 illustrate the application of the tool, respectively in partially opened and closed positions, to one character of poppet valve mountings, common to some types of automobile engines; and

Figure 7 illustrates the application of the tool to another form of poppet valve mountings, common to other types of automobile engines, and frequently termed "valve-in-the-head" construction, the left side of the view also illustrating the application of an auxiliary equipment element, which may or may not be combined with the tool.

Referring first more particularly to Figures 1 to 4, the numerals 10 and 11 designate upper and lower handle members, respectively, which may be suitably shaped longitudinally and transversely, and being preferably of channeled construction for lightness, the said handle members being crossed and pivoted together intermediate, as at 12, and providing forwardly disposed jaw extensions or arms 13 and 14.

The numerals 15 and 16 designate the effective tool jaws, which at their outer extremities are provided with the outwardly opening complementary slots 17 and 18, and their inner ends being pivotally connected, in positive or non-slidable relation, to their complementary operating handles 10 and 11, as at 19 and 20, rearwardly of the pivotal means 12 for the crossed handles, the pivotal elements 19 and 20 preferably being in the nature of axis pins, having one of their ends threaded for screwthreaded attachment and their other end provided with a milled head 21, whereby the jaws may readily be attached and detached, as will be obvious, for transposition or replacement purposes.

As shown, these jaws may embody flat blanks provided with marginally inturned longitudinal flanges 22, which flanged construction, although not at all essential, is more especially desirable with reference to the modified type of Figure 4^a, and the inner non-slidable or positive pivotal connections with the handles may be provided for by

the spaced ears 23. The inside faces of the outer extremities of the jaws may be provided with outwardly opening semi-circular seats 24 and 25, with the inner faces of the latter grooved, as at 26, for snugly seating a coil of the spring or its cupped washer, and for seating such cupped washer, one of the said seats may be of greater diameter than the other, the drawings showing the 10 seat 25 as being of greater diameter than the seat 24. This actual form of seating means, however, is not strictly essential, and is not shown as being employed with the modified structure of Figure 4^a. The tip ends 27 of 15 the jaws may preferably converge slightly towards each other, for facilitating the guiding and centering of the jaws relatively to the coil spring to be gripped thereby.

The forward portions of the jaws 15-16, 20 rearwardly of their slotted ends, are slidingly connected to the forward ends of the lever arm extensions 13-14 of the pivoted handle members. Although this is an important feature of my improved preferred 25 construction, it is nevertheless obvious that these sliding connections may be accomplished in varied ways.

For several reasons, however, including 30 a facile manner for attaching and detaching the jaws relatively to their supporting handles and extension lever arms, I have found it to be a very simple and expedient arrangement to provide narrow apertures or slots 28 and 29, extending longitudinally of the 35 jaws, adapted to freely receive angularly disposed necks or shanks 30 and 31 formed at the ends of the lever arms 13-14, which necks or shanks are suitably headed or terminate in cross-lugs 32 and 33, and at their 40 joinder with the lever arms 13-14 they form the shoulder portions 34, suitably spaced by the neck portions from the cross-lugs.

The cross-lugs in assembly are adapted to 45 be disposed, across the slots, transversely of the outer faces of the jaws, and the shoulder portions 34 are analogously disposed to project transversely of the inner faces thereof, the arrangement thus forming a sliding interlock between the jaws and their lever 50 arms.

It will be noted that the width of these cross-lugs 32-33 is less while their length is greater than the width of the slots 28-29, so that in attaching or detaching the jaws 15-16, by holding them at right angles to the lever arms 13-14, the said cross-lugs 55 may be passed through their complementary slots 28-29, but they will provide for a sliding interlock or connection when the jaws are disposed longitudinally of the lever arms and are pivotally connected at their inner ends to the handles at 19 and 20.

In operation, therefore, the effect is that, 60 when the handles 10-11 are operated towards each other, the axis pins 19 and 20

function as swinging fulcrums to push the inner ends of the jaws towards each other, while the cross-lugs 32-33 function as sliding fulcrums to pull the outer ends of the jaws towards each other, the movements thus 70 being made uniform and maintaining the substantial parallelism of the jaws at all times. In the reverse movements, the swinging fulcrums exert a pulling force on the inner ends of the jaws, while the sliding 75 shoulders 34 exert an opening pushing force on the outer end portions thereof.

Any suitable resilient means may be interposed between the parts to normally move 80 the handles and jaws to their opened out positions, which feature is simply illustrated by a light wire spring 35 having its central portion coiled around the pivot pin 12, with its projecting ends divergently engaging the 85 channeled handles.

Likewise, any suitable means may be employed for holding the parts locked at any 90 adjustable position, and in all of the views of the drawings excepting Figures 2, 3 and 4^a, a modified means being shown at Figure 90 4^a, this locking feature is simply illustrated by a pivotally hung ratchet, or toothed bar 36, operating in a manner which is obvious.

Also, at 37, there is shown a pivotally hung 95 hook element, which may or may not be employed as combined with the tool proper, and the functioning of which will herein-after appear.

All of these elements 35, 36 and 37 are 100 housed by the channeled handle members, and suitable means may be employed, illustrated by the wire springs 38 and 39, for holding the elements 36 and 37 in their folded-up positions.

In the structure shown at Figure 4^a, the 105 slight modification relates to the seating means or limiting stops for the coil spring to be handled with the tool, substituted for the equivalent seating means 24 and 25 of the other views, and it also relates to a modified 110 means for locking the parts in any adjusted position, which latter feature or its equivalent, although only shown in connection with Figure 4^a, may in fact be used with all 115 forms of the tool.

In this view I have shown a pair of inwardly projected shouldering lips or lugs 40, to replace the seats 24-25, which lugs may be conveniently formed by slitting the 120 jaw plates to provide a tongue that is bent over to project inwardly of the jaw, leaving the aperture 41, although such lugs could be formed in other ways, and they function to provide abutments against which adjacent coils of the spring engage.

On the other hand, the lugs 40 could be dispensed with and a single central lug 42 formed, which would cooperate with the marginal flanges 22, at the forward ends of the jaws, to provide engaging abutments 120 130

for the adjacent coils of the spring, the lug 42 resulting from bending over, and clipping off if too long, the tongue formed by slitting the jaw plate to provide the slot 28. However, instead of clipping off a portion of this tongue 42, the longer tongue could itself be slit centrally and longitudinally, for a limited distance from its free end, and its separated sections curved laterally, in opposite directions, to provide semi-annular seats, more analogous to the seating means 24-25, the foregoing applying to the lower jaw 16 also.

43 indicates a locking cam disk eccentrically pivoted, as at 44, adjacently of the inner end of one of the slots 28 or 29, which disk is provided with an operating part or knob 45, an edge face cam surface 46 and a suitably cut-away edge face portion 47.

At Figure 4^a, the position of the cross-lug 32 indicates that the jaws have been moved to almost their extreme closed-up positions. If now the cam disk 43 be partially rotated in clockwise direction, the cam face 46 will be moved into wedging engagement with the angular shank 30, or the neck between the arm 13 and its cross-lug 32, so that the jaws will be held locked in that position, until the cam disk is rotated in a reverse direction, as will be obvious, and the object of the recessed face 47 is to provide clearance for the shank 30, when the jaws are moved to their full open positions. As a matter of fact, however, the cut-away portion of the disk could be of larger or smaller dimensions, if desired, than that actually shown by the recessed portion 47.

Figures 5 and 6 are fragmentary views of cylinder walls 48 roughly illustrating one common form of valve mountings, with the improved tool shown more or less in opened and closed positions as associated with a valve spring thereof; whereas Figure 7 is an analogous view roughly illustrating a cylinder head 49 with the so-called "valve-in-the-head" type of valve mountings, and with the tool applied in two different relations.

Both of these constructions embody a poppet valve 50, with a retaining pin 51 through the end of its stem opposite the valved head, a coil valve spring 52 encompassing said stem, between said pin and an abutment face of the motor body, and a cupped washer 53 for seating the spring end adjacent the said retaining pin. In the constructions of Figures 5 and 6, the valve is actuated by a cam operated push rod directly supporting the stem of the valve, but in the "valve-in-head" type of Figure 7, the vertical disposition of the stemmed valve is reversed, with the valve head down and the cupped washer uppermost, so that the valve is actuated by means of a rocker bar mounted on a shaft,

as at 54, one arm 55 of the rocker bar engaging the valve stem, while the other arm 56 thereof is engaged by a reciprocating rod 57 that is actuated by a supporting cam operated push bar 58, and all of which is fully understood.

In employing the tool in connection with the valve mountings of Figures 5 and 6, and with particular reference to the tool jaw construction of Figures 1 and 2, and the same principles being involved in the slightly modified form of Figure 4^a, it will be seen that the jaws 15-16 may be caused to grip the spring 52 in bridging or spanning relation, with the larger seating means 25 snugly receiving the cupped washer 53 and with the smaller seating means 24 snugly receiving the coil at the other end of the spring, although the end of the jaw 15 may be inserted between coils, as will be evidenced from Figure 7, and it furthermore being observed that the slotted ends of the jaws encompass the valve stem.

If now the handles 10-11 are moved towards each other, the spring 52 will be compressed in a truly axial direction and, therefore, without any tendency towards buckling, because the outer ends of the jaws do not have arcuate movement, as do the outer ends of the lever arms 13-14, but the jaws are bodily moved in continuing substantial parallelism, owing to the pivotal connection of their rear ends to the handles and their sliding connection towards their forward ends with the outer ends of the pivotal lever arms 13-14, all as hereinbefore fully set forth.

The spring 52 being now compressed, as at Figure 6, the pin 51 may readily be withdrawn, so that the stemmed valve may be removed, and, with the rack bar 36 or any equivalent thereof holding the parts locked in their adjusted positions, it will be apparent that the spring 52 itself will be firmly held in its compressed state, so that the tool functions as a carrier support therefor, either in removal or assembling operations.

The tool functions in an analogous manner with reference to the "valve-in-head" type of construction of Figure 7, excepting that in this case the jaws 15-16 have been taken off and replaced in transposed positions, the jaw 16 being now pivoted to the upper handle 10 and slidably connected with the lever arm 13, while the jaw 15 is likewise associated with the handle 11 and lever arm 14, so that the larger seating means 25 still receives the cupped washer 53, or its equivalent, which is now located uppermost with reference to the valve mounting, and this view also illustrates the adaptability of the smaller seating means 24 for snugly receiving a coil of the spring 52 that is not necessarily an end coil.

Of course, separate tools could be made and marketed for specific use in connection with the different types of valve mountings, but, as a matter of fact, I aim to supply separate sets of paired jaws of different types and dimensions, for interchangeable purposes with an individual crossed-handles unit, one set of which may be taken off and replaced by another set as desired.

Also, at the left side of Figure 7, I have illustrated the functioning of the pivotally hung hook member 37, when it is desired to combine it with the improved tool, this hook member being designed to elevate the left arm 56 of the rocker bar, against the pressure of the valve spring 52 on its other arm 55, whereby the actuating rod 57 may be facilely removed, from association with the push bar 58 and rocker arm 56, a task that is difficult to accomplish without the use of some such elevating tool.

Although I have thus fully disclosed the improvements, it will nevertheless be understood that I do not restrict myself to all of the details exactly as disclosed, excepting as they may come within the terms of the claims, or equivalent elements or combinations thereof, or as fairly interpreted in the light of the specification if necessary, for it is obvious that alterations may be made without departing from the spirit of the invention. For instance, as I have heretofore stated, varying forms of seating means may be provided for by the jaws to receive the engaged coils of the springs or cupped washer, and varying forms of locking means may be employed for holding the parts at any adjusted position.

What I do claim, as new and patentable, is:—

1. In a coil spring compressor and carrier holding tool embodying crossed arms, with a pivotal connection therebetween, forming a pair of rearwardly projected operating handles, relatively to said pivotal connection, and forwardly continuing jaw engaging levers, the combination of a pair of spaced bodily movable and detachable jaws longitudinally straddling said pivotal connection, the forward end of each of said levers and of each of said detachable jaws being provided with coacting means for slidably connecting the same, when longitudinally disposed in complementary relation, while also providing for the facile attaching and detaching of each of said detachable jaws when disposed in appropriate angular relation, and pivotal means for detachably connecting the rear end of each of said jaws, in non-slidable relation, to its complementary one of said operating handles.

2. In a coil spring compressor and carrier holding tool, the combination of a supporting unit, for the jaws of the tool, embodying crossed arms, with a pivotal connection

therebetween, forming a pair of rearwardly projected operating handles, relatively to said pivotal connection, and forwardly continuing jaw engaging levers terminating at their forward ends in out-turned shanks with transversely disposed heads, a pair of spaced bodily movable and detachable jaws longitudinally straddling said pivotal connection, the forward portion of each of said detachable jaws being provided with a longitudinal slot for encompassing the shank of its complementary jaw engaging lever, to provide a sliding connection therebetween when longitudinally disposed in complementary relation, and also providing for the facile attaching and detaching of each of said detachable jaws when disposed in appropriate angular relation, and pivotal means for detachably connecting the rear end of each of said jaws, in nonslidable relation, to its complementary one of said operating handles.

3. In a coil spring compressor and carrier holding tool embodying crossed arms, with a pivotal connection therebetween, forming a pair of rearwardly projected operating handles, relatively to said pivotal connection, and forwardly continuing jaw engaging levers, the combination of a pair of spaced bodily movable jaws, longitudinally straddling said pivotal connection and so connected to their complementary said handles and levers as to cause approximately parallel closing and opening movements of said jaws concurrently with the respective closing and opening movements of said handles, resilient means normally tending to open both said jaws and handles, and means for adjustably holding both said jaws and handles against opening movements while permitting of further closing movements of the same, which said means embodies a ratchet bar pivoted at one end to one of said handles and at its other end extending through a coacting slot formed through said other handle.

4. In a coil spring compressor and carrier holding tool embodying crossed arms, with a pivotal connection therebetween, forming a pair of rearwardly projected operating handles, relatively to said pivotal connection, and forwardly continuing jaw engaging levers, the combination of a pair of spaced bodily movable and detachable jaws longitudinally straddling said pivotal connection, the forward end of each of said levers and each of said detachable jaws being respectively provided with shank and slot means for slidably connecting the same, when longitudinally disposed in complementary relation, while also providing for the facile attaching and detaching of each of said detachable jaws when disposed in appropriate angular relation, pivotal means for detachably connecting the rear end of

each of said jaws, in non-slidable relation, to its complementary one of said handles resilient means normally tending to open both said jaws and handles, and means for adjustably holding both said jaws and handles against opening movements while permitting of further closing movements of same,

which means embodies a ratchet bar pivoted at one end to one of said handles and at its other end extending through a coacting slot formed through said other handle. ¹⁰

In testimony whereof I affix my signature.

DAVID C. FEATHER.
